UNITED STATES PATENT OFFICE.

LEONARD HENKLE, OF ROCHESTER, ASSIGNOR TO CHARLES STANFORD
UPTON, OF NEW YORK, N. Y.

WICK-RAISER FOR LAMPS.

SPECIFICATION forming part of Letters Patent No. 415,108, dated November 12, 1889.

Application filed August 22, 1889. Serial No. 321,592. (No model.)

To all whom it may concern:

Be it known that I, LEONARD HENKLE, a citizen of the United States, residing at Rochester, county of Monroe, and State of New York, have invented certain new and useful Improvements in Wick-Raisers for Lamps, of which the following is a specification.

My present invention is an improvement on the wick-raiser for lamps shown in Letters Patent No. 398,725, dated February 26, 1889; and it consists in providing the operating-shaft with a disk or projection for holding down the rod to its seat.

In the accompanying drawings, Figure 1 is a vertical sectional view of a central-draft lamp of the Rochester pattern, to which I have shown my invention applied. The hollow removable thimble is not shown. Fig. 2 is a similar view of a detail to a larger scale.

The bowl or fount 1 is shown provided with customary central-draft tube 2, which the wick 3 surrounds. The outer wall of the wick-chamber is made by the ring or cylinder 4, carried by the shell or case 5 of the burner, which forms a chimney-support. The latter is removably applied to the fount 1 by bayonet or similar joint.

6 is the wick-rod or draw-bar, screw-threaded at its lower part to enter a correspondingly-threaded hole in an arm 7 of the wick-ring 8,

which tightly clasps the wick. The tube 2 guides the wick and its ring in their vertical motion. The upper end of the draw-bar 6 has bearing in the top of the fount. Near its top the rod 6 carries a toothed pinion 12, 35 gearing with a similar pinion 13 on the upper end of a shaft 14. Said shaft passes entirely through the fount and has cylindrical bearing therein, which prevents contact of the shaft with the oil of the lamp. The top of the bearing projects above the joint at 15 to support the shaft and pinion 13 in proper position. At the lower end the shaft bears a hand-nut 15. In order to hold the draw bar or rod 6 down, the shaft 14 has a disk or projection 40 17 fixed to its upper end, of greater diameter than pinion 13, so as to project over the pinion 12 on rod 6. 45

Having thus described my invention, the following is what I claim as new therein and 50 desire to secure by Letters Patent:

The combination of the lamp-fount, the wick-raising rod and shaft, both having bearing therein, and a disk or projection on said shaft for holding down said rod, substantially 55 as set forth.

LEONARD HENKLE.
